UNITED STATES PATENT OFFICE.

JEFFERSON H. MILLSAPS, OF WASHINGTON, DISTRICT OF COLUMBIA.

VISIBLE ALARM FOR AUTOMOBILES.

1,202,202.

Specification of Letters Patent.

Patented Oct. 24, 1916.

Application filed June 14, 1915. Serial No. 34,058.

To all whom it may concern:

Be it known that I, JEFFERSON H. MILLSAPS, a citizen of the United States, residing at Washington, in the District of Columbia, 5 have invented a new and useful Visible Alarm for Automobiles, of which the following is a specification.

The object of my invention is to provide a novel visible alarm for automobiles by 10 which a visible signal will be caused to operate in consequence of the starting of the vehicle by any one without authority from the owner.

It is an object of my invention to provide 15 a novel form of visible signal which may be displayed at either or both ends of the machine which will indicate that it is stolen and result in the arrest of persons driving it without authority.

20 It is an object of my invention to provide novel means for causing the operation of such a signal by the movement of some part of the automobile which must be operated to start the machine; to provide novel means 25 for the locking of such a device in operative or inoperative position; to provide novel means adapted to operate the means for displaying the signal in the event that the primary operating means should be tampered with or the lock broken; and to provide 30 novel means by which the device may be set to operate at a predetermined period subsequent to the starting of the machine.

It is a further object of my invention to so 35 incase my signal mechanism as to make its destruction difficult and to provide signaling mechanism of such intricacy as to discourage tampering with it and thus cause persons contemplating the theft of an automobile to choose some other machine than one equipped with my visible alarm.

I attain the objects of my invention by suitable mechanism such as is illustrated in the accompanying drawings, in which—

45 Figure 1 is a top plan of the invention applied to an automobile chassis; Fig. 2 is a section on line 2—2 of Fig. 1; Fig. 3 is a longitudinal section on line 3—3 of Fig. 1; Fig. 4 is a diagrammatic perspective showing details of the mechanism operated by the clutch lever; Fig. 5 is a fragmental sectional view approximately through the central portion of the face of the clock mechanism; Fig. 6 is a detail of the clock hand mechanism; Fig. 7 is a detail of member 40; Fig. 8 is a detail of the means for locking

member 31; Fig. 9 is a rear view of the automobile showing the visible alarm in displayed position; Fig. 10 is a detail sectional view of the visible alarm signal member and 60 means incasing same; and Fig. 11 is a detail of the mounting of the clock hand and its electrical connections, certain elements being shown in diagram.

Like characters of reference indicate like 65 parts throughout the several views.

Broadly considered, my invention comprises a visible alarm or signaling display means normally retained in a non-displayed or non-signaling position or condition; 70 means operatively connecting the visible signaling means with and adapted to be operated by the drive shaft of the automobile but normally out of operative engagement with the drive shaft or other suitable moving element of the vehicle; key-controlled means adapted to place the lever or other suitable element used in starting the automobile in operative connection with the visible signaling means to effect its operative engagement 75 with the drive shaft to actuate the alarm; and auxiliary operatively-dependent key-controlled means having means for regulating its time for completing operation and having an independent key control, the said 80 means being adapted to operatively connect the visible alarm or signaling means with the drive shaft in the event of the failure of the primary operating mechanism, through tampering or otherwise, to effect 85 such operative connection, or which may be set to operate the mechanism, if preferred, at a suitable predetermined time subsequent to the starting of the automobile instead of simultaneously with its starting. 95

It is within the contemplation of my invention to adapt mechanism to operatively connect with any suitable moving parts or any suitable starting elements other than the specific element shown, the drawings being 100 merely illustrative of my preferred form of applying the invention to an automobile.

Referring to the accompanying drawings, I provide a suitable visible alarm signal 1, mounted by a pivotal portion 2 within a suitable casing 3, provided with a suitable display opening or window 5', the casing 3 being fastened to some visible portion of the automobile, such as the axle, by metal straps 105 4 or other suitable means. My visible alarm signal 1 is normally held in non-displayed position by a suitable spring 5. Suitable

means for moving the signal 1 from non-display to display position to make it visible to the public is provided, such as a gear 6 attached to pivot portion 2, the gear being disposed at one side of signal 1. Gear 6 may be rotatably engaged by a chain 7, the latter forming a continuation of a suitable chain or cable 8. Cable 8 is contained within a suitable tube or casing 10 to prevent its being tampered with, and may be extended toward or to casing 26, within which is a rack 10 which normally is in an inoperative position. Mounted on the drive shaft D, I provide a suitable gear 11 with which rack 10 may be thrown into engagement by means to be subsequently described. The engagement of rack 10 with wheel 11 when the vehicle is started will draw the rack over, exerting a pull on cables 8 and thus causing a display 20 of signals 1, as will be understood by reference to Figs. 2 and 10. To insure maintenance of the signals in displayed position after once being operated, I provide a suitable pawl 24, controlled by spring 25 and disposed in position to engage catch or shoulder 62 on rack 10 and retain it there until released by the owner of the vehicle, who alone will have access to it through door 27 which is fastened by a suitable lock indicated at 28. 30 It is within the contemplation of my invention to provide visible alarm signals in position to be displayed from both the front and rear ends of the vehicle, as indicated in Fig. 1, or the signal may be displayed at one 35 portion of the vehicle where desired. This may be at any suitable portion of the vehicle.

To operate the foregoing mechanism, I provide suitable key-controlled means adapted to place the clutch lever or other suitable element used in starting the automobile, in operative connection, through the agency of rack 10 and gear 11, with the means for operating the visible signal. The particular means illustrated in Fig. 4 to accomplish this 40 object consists of a suitable lug or stop 12 on rack 10, against which rod or link 13 will operate when pressed toward the shouldered end of rack 10, to depress member 10 in order that it may engage and be operated by gear 45 11. Gear 11 is a suitable gear provided on drive shaft D, and held in rigid engagement with the drive shaft. Attached to the free end of rod 13 is a link 14 connecting it with bell crank 15, which in turn is operatively 50 connected by member 16 with one end of pivotally mounted member 17, the other end of which is keyed or suitably attached to lock 18. Lock 18 is provided with a sliding bolt 21, operated from keyhole 22, any suitable lock and key being available for the 55 purpose, the lock mechanism not being claimed except as combined with other elements of my invention. Lock 18 is suitably mounted in a case 19 and is retained in its 60 normal position by a spring 20. When slid-

ing bolt 21 has been locked in its outward position it will be operated by a projecting portion of clutch lever C, but when in retracted position, the operation of member C will not cause the signaling mechanism to 70 operate, as member C will clear lock 18.

I further provide auxiliary means adapted to operatively connect the drive shaft with the means for displaying the visible alarm signal, this means however being operatively 75 connected with rack 10, but provided with an independent key control apart from the primary means for operating rack 10 and further provided with mechanism by which its time of completing effective operative 80 connection with rack 10 may be regulated to operate at a predetermined time subsequent to the operation of the clutch lever C or other suitable element of the vehicle used in setting the machine in motion. It is designed as an 85 auxiliary but operatively-related means adapted to effect connection between the drive shaft and the signal actuating means which may be set to cause the operation 90 of the signal should the primary mechanism be tampered with or for any reason be inoperative or be locked in inoperative position. In the form of the invention illustrated in Fig. 4, this auxiliary time-controlled operating means is arranged to 95 operatively connect rack 10 with a portion of the clutch located substantially apart from the portion adapted to connect with sliding bolt 21. The operation of the signal is insured by such auxiliary signal operating 100 means in the event that the primary and more exposed mechanism should be tampered with and rendered inoperative as well as when the latter mechanism is intentionally set in inoperative position. As my auxiliary 105 signal operating means has an independent key control it may be set to operate or not as desired, and it may be also arranged to operate at such predetermined period subsequent to the starting of the automobile, as 110 may be desired. The mechanism receives its impulse from clutch lever C or such other suitable element used in starting the vehicle as it may be operatively connected to.

Referring to the drawings, Fig. 8, I provide a suitable lock 29 at a suitable portion 115 of clutch lever C substantially distant from the portion of such lever adapted to operatively engage with sliding bolt 21 of the primary signal operating means. Lock 29, 120 which may be any suitable lock structure (the lock itself not being claimed as my invention) is operated by a suitable key adapted to be inserted in keyhole 30. The bolt of the lock is adapted to be turned into 125 or out of engagement with a suitable slot 32 in a slidable rod or bar 31. When in unlocked position, rod 31 is freely slidable through lock 29 and consequently the operation of clutch lever C does not set in motion 130

the signal operative mechanism of which rod 31 is a member. Rod 31 is suitably jointed at 33 to link 34. Link 34 is suitably attached to one end of bell crank 35. To the other end of bell crank 35 is attached a suitable rod or wire 36 having a suitable spring 37 attaching it to bell crank 38. Member 38 is resiliently held in its normal position by spring 39, mounted on plate 64 covering the face of a suitable clock indicated by T. Clock T may be of any suitable construction, only the novel mechanism set forth in the drawings, Figs. 4, 5, 6, 7 and 11 being my invention, the rest of the clock structure being of any suitable design.

Clock T may be provided with a suitable minute hand 44 (no hour hand is essential). Pivotedly mounted in its outwardly turned ears 42 is a suitable pivot member 40 supported by pivot 41. Mounted in the outer end of member 40 is a pin 39, slidably projecting through a suitable opening in plate 64, the head of pin 39 being disposed to engage over the adjacent end of member 38, as shown in Fig. 5. Spring 45 serves to retain the elements in normal position. In the upturned slotted end 43 of pivot bar 40 is mounted a suitable slide hook 46, held normally as shown in Fig. 6 by a suitable spring 47, one end of which is attached to a shank of the hook while the other end is disposed against end portion 43. Slide 46 is normally out of engagement with circular rack 48 over which it travels in spaced relation.

I provide means for retaining slide hook 46 in engagement with rack 48 when pivot member 40 is tilted to effect such engagement. This means may comprise a pawl 50 having a shoulder 51 on which the head of pin 39 may engage and rotate when drawn to its outer position. Spring 49 supports pawl 50 in normal position. A wire 52, disposed over suitable rollers 53 and 54 connects member 50 with member 55 which may be suitable wire or other connecting element adapted to operatively connect the end of rack 10 with a suitable metallic element or core 56 adapted to be magnetized by a suitable solenoid 57 when an electric circuit is effected. Contact members 59 and 61 are normally out of engagement. When in contact with each other they complete an electric circuit, and energize solenoid 57 in consequence, which in turn exerts a pull on member 56. The two contacts which are normally out of engagement are disposed in position to converge in the event of slide hook 46 engaging rack 48, thus being held in stationary position while the clock hand 44 continues its travel, the time required to bring about a meeting of contacts 59 and 61 being predetermined by their normal distance apart from each other. Contact 61 is mounted on slide hook 46. Contact 59 is mounted on clock hand 44. The mechanism

is illustrated diagrammatically in Fig. 4. In order that wire 58, extending from contact 59 and wire 60 extending from contact 61 may not become entangled, they are extended parallel with clock hand 44 and fastened to members 71 and 70, respectively, which are mounted on an insulated portion of the clock hand, as illustrated in Fig. 11. The clock hand 44 is mounted on a suitable arbor 65 operated by the clock mechanism in suitable manner. Referring to Fig. 11, member 66 is the clock face or partition on which rack 48 is mounted. The electrical circuit which is effected by the meeting of contacts 59 and 61 comprises a suitable battery B, from which extends a wire 76 connecting it with brush 68. Brush 68 is disposed to contact with a suitable contact disk 69 secured to the arbor 65 effecting electrical connection with member 70, from which the current may pass to wire 60 and thence to contact 61. The current passes from contact 61 through contact 59 (when they meet) and thence to wire 58, and from wire 58 to member 71, and thence to disk 72 with which member 71 contacts. Disk 72 is mounted on arbor 65 but is insulated from it. From disk 72 the current passes to brush 73, and thence to wire 74 to the solenoid 57. The circuit from solenoid 57 is completed by wire 75 which extends from the solenoid to the opposite side of battery B.

Referring to Fig. 4, when rod 31 is locked in fixed position to lock 29, carried by lever C or other suitable starting element of the vehicle, operation of lever C in starting the automobile exerts a pull on rod 31, link 33, bell crank 35, rod 36, bell crank 38 and through the engagement of the latter element with the head of pin 39 tilts pivot bar 40 and causes slide hook 46 to engage in rack 48 on the clock face. It is retained in such engagement by the operation of pawl 50, shoulder 51 of which engages under the head of pin 39, thus holding pivot bar 40 in tilted relation to clock hand 44 while the hand continues to turn. The clock hand may, for example, continue to travel for five minutes before the signal is operated. During the five minutes the slide hook 46 is being gradually pulled through slotted end 43 of pivot bar 40, until contact 61 carried by member 46 meets contact 59 on the clock hand 44, thereby closing the electric circuit set forth in the preceding paragraph, and causing solenoid 57 to exert a pull on core 56. The latter thus, through the medium of member 55 connecting it with rack 10, draws rack 10 into engagement with gear 11, mounted on drive shaft D, and which, as hereinbefore described operates the visible alarm signal through the medium of cables 8. The visible alarm signal 1 through the display of the word "Stolen" or some similar notification, informs the public that the automobile has

been taken surreptitiously or without authority from the owner, and is intended to lead to the arrest of the person who has thus taken the vehicle.

5. It is to be understood that the form of my invention herewith shown and described is to be taken as a preferred example of the same, and that various changes in connecting elements, arrangement and number of parts 10 may be resorted to without departing from the essence of the invention or the scope of the claims, and are within the contemplation of my invention.

What I claim is:

15. 1. In combination with a vehicle, a signal normally in non-displayed position, means adapted to operatively connect such signal with the drive shaft of the vehicle, means operatively connecting the aforesaid means 20 with a starting element of the vehicle, and key-controlled means adapted to regulate the time at which the signal shall be displayed subsequent to starting of the vehicle.

25. 2. In combination with a vehicle, a signal normally in non-displayed position, key-controlled means adapted to operatively connect it with a moving element of the vehicle, auxiliary key-controlled means adapted to operatively connect the signal with a moving 30 element of the vehicle at a predetermined period subsequent to the starting of the vehicle, substantially as described.

35. 3. A normally non-displayed alarm signal in combination with means adapted to operatively connect it with the drive shaft of a vehicle to cause its display said means being normally out of engagement with the drive shaft, key-controlled means operatively connecting the aforesaid means with a starting 40 element of the vehicle and auxiliary key-controlled and time regulated means operatively connecting the above-described display-signal operating means with a starting element of the vehicle at a point substantially distant from the first-mentioned key-controlled means.

4. Normally non-displayed alarm signals positioned at opposite ends of a vehicle, means adapted to operatively connect said signals with the drive shaft of a vehicle to 50 cause their display, means operatively connecting with the starting element of a vehicle to actuate same, and means operatively connected with the means for displaying the signals to cause their display at a variable 55 but governable predetermined period subsequent to the starting of the vehicle, whereby tampering with the primary operating means will not avert the display of the alarm signals.

60. 5. Normally non-displayed alarm signaling means positioned at one or both ends of a vehicle, means resiliently retaining same in non-displayed position, means adapted to operatively connect the alarm signaling 65 means with a moving element of the vehicle to cause their display, means to actuate same on movement of a starting element of the vehicle said means having key control, and auxiliary means operatively connecting the 70 signal operating means with a starting element of the vehicle at a separated point said means having an independent key control, and time controlled means operated by the latter mechanism to cause the operation 75 of the signaling means at a period subsequent to the starting of the vehicle.

6. In combination with a visible alarm for vehicles, means normally out of engagement with a moving element of the vehicle and 80 adapted to engage with and be operated by same to display the alarm visibly, key-controlled means adapted to operatively connect the aforesaid alarm operating means with the moving element of the vehicle, time-controlled means adapted to complete the operative connection of the aforesaid key-controlled means with the alarm-operating means at a variable but governable predetermined time subsequent to the starting of 90 the vehicle.

JEFFERSON H. MILLSAPS.
